UNITED STATES PATENT OFFICE.

JULIUS ALWIN LOTH, OF UTRECHT, NETHERLANDS.

ARTIFICIAL LIMB AND THE LIKE.

1,390,915.

Specification of Letters Patent. Patented Sept. 13, 1921.

Application filed May 7, 1918. Serial No. 233,066.

To all whom it may concern:

Be it known that I, JULIUS ALWIN LOTH, manufacturer of surgical instruments, a subject of the Queen of the Netherlands, 5 and residing at Utrecht, Netherlands, have invented certain new and useful Improvements in or Relating to Artificial Limbs and the like, of which the following is a specification.

10 As is well known, natural knee and elbow joints are not simple hinged joints, but the ends of the upper and lower bones of the arm and leg roll on one another, the shape of the rolling faces being such that the 15 arm or leg is shortened or lengthened when bending or straightening them, respectively. Consequently artificial limbs that comprise pivotally connected parts for clasping the upper and lower parts of the arm or leg 20 have the defect that when bending and straightening them the stump has to move axially in the casing surrounding it; because the artificial limb maintains its length while the natural lower part of the limb 25 moves axially relatively to the upper part of the limb.

Joints for orthopedic knee-stretching devices are known intended to imitate the movement of the natural joint by means of 30 a curved guide. These joints, however, could not heretofore be used for making artificial limbs, because their lower part does not move axially relatively to the upper part and the construction was not suitable, 35 particularly, the pins wore quickly in their guides and broke, and also the friction in the joints was too great.

A primary object of my invention is to 40 provide an improved joint to which these defects are not attached, so that it is adapted for use in artificial arms and legs and in medico-mechanical apparatus for moving stiff knees and elbows. I attain this end by using two guiding grooves the 45 one of which corresponds in shape to that of the rolling face of the natural bone and the other being inclined against the axis of the limb in such a manner that during the bending of the joint the actual center of rotation moves to the rear side of the part bearing said inclined groove and balls for connecting the two parts of the joint, the one half of each ball running in the one part, and the other half in the other part of 55 the joint.

To this and other ends my invention consists of the construction, arrangement and combination of parts described hereinafter and pointed out in the claims.

Several embodiments of my invention are 60 diagrammatically represented by way of example in the accompanying drawings, wherein:

Figures 1 and 2 are side elevations showing the joint in two different positions, the 65 front part of the joint having been removed,

Fig. 3 is a vertical section of the joint as shown in Fig. 1, and

Fig. 4 is a diagram showing the action 70 of a natural knee joint;

Fig. 5 is a modified form of a joint according to my invention.

Referring to the drawing, the bar *a* is for attachment to the upper part of the artificial arm or leg, while the bar *b* is for connection with the lower part of the artificial arm or leg. In the embodiment of the bar *b* is made fork-shaped by means of a cap *c* (Fig. 3), this being removed in Figs. 1 and 2. The bar *a* has in one or, as shown, in 75 both sides a curved groove *d* which corresponds in shape to that of the rolling face *e* (Fig. 4) of the bone of the natural arm or leg. A ball *e* runs in this groove *d*, approximately half of it being located in this 80 curved groove and the other half in a recess *f* in the bar *b* of the lower part of the leg or arm. The second ball *g* is half in a recess *h* in the bar *a* and half in a groove *i* in the bar *b*, said groove being inclined against 85 the axis of the bar *b*. If a cap *c* is employed, as shown in the drawing, its side facing the bar *b* is formed correspondingly, so that the guidance is the same on both 90 sides. In the extended position shown in 95 Fig. 1 the ball *g* is located close to the extreme end of the groove *i*, and the ball *e* is located near the lower end of the curve *d* remote from the center of the joint. When bending the joint (Fig. 2), the ball *e* rolls 100 in the groove *d* and arrives into the part of this groove located nearest the center of the joint, the groove *i* sliding simultaneously along the ball *g*. Thereby the artificial limb is shortened *i.e.* the lower part is 105 raised against the upper one, said shortening corresponding to the distance the groove *i* has moved relatively to the ball *g*. A comparison with Fig. 4, in which the lower part *k* of the limb is shown in three different po- 110

sitions relatively to the upper part *m*, shows that the movement corresponds exactly to that of the natural joint.

My improved joint is particularly adapted for use in artificial limbs for attachment to short stumps below the knee capable of carrying loads. The construction of such prothesis was heretofore particularly difficult because, as mentioned above, when the 10 leg was being bent the stump moved axially and was consequently lifted from its seat, so that could not be used for carrying a load. In this case only the protuberance of the thigh or seat bone could be used. When 15 the improved joint is employed the stump always remains in place on its seat and, consequently, when capable of carrying a load can be used for this purpose.

For preventing the knee or elbow being 20 bent through too large an angle a stop *n* is provided on the part *b* sliding in a groove or slot *n*¹ of the part *a*.

In the embodiment (Figs. 1-3) the 25 groove *d* is in the part *a* and the grooves *i* in the parts *b* and *c*. Of course the reverse arrangement may be obtained if desired, as shown in Fig. 5.

Having described my invention, I claim 30 and desire to secure by Letters Patent.

30. 1. In a joint of the character described for artificial limbs the combination of two parts guided against each other by two guiding grooves the one of which corresponding in shape to that of the rolling face of the 35 natural bone and the other being inclined against the axis of the limb in such a manner that during the bending of the joint the actual center of rotation moves to the rear side of the part bearing said inclined groove, 40 and means for holding the two parts together.

2. In a joint of the character described for 45 artificial limbs, the combination of two parts each being provided with a recess and a guiding groove, the one of said guiding grooves corresponding in shape to that of the rolling face of the natural bone and the

other being inclined against the axis of the limb in such a manner that during the bending of the joint the actual center of rotation moves to the rear side of the part bearing said inclined groove, balls located approximately half in a recess in one part and on a groove in the other part and means for holding the two parts and the balls together. 50 55

3. In a joint of the character described for artificial limbs, the combination of a joint part to be attached to the upper part of the artificial limb, a second joint part to be attached to the lower part of the artificial 60 limb, the two joint parts being guided against each other by guiding grooves, one of said grooves being provided in each of the said joint parts, the groove of the first named joint part corresponding in shape to 65 that of the rolling face of the natural bone and the groove of the second named joint part being inclined against the axis of the lower part of the artificial limb in such a manner that during the bending of the joint 70 the said lower part is raised against the said upper part of the artificial limb, and means for holding the two parts together.

4. In a joint of the character described for artificial limbs, the combination of one 75 part having a recess and a groove in opposite faces, a forked second part embracing the recessed grooved portion of the former part and having grooves and recesses on the faces adjacent thereto, the grooves in the 80 one part corresponding in shape to that of the rolling face of the natural bone and the grooves on the other part being inclined against the axis of the limb in such a manner that during the bending of the joint 85 the actual center of rotation moves to the rear side of the part bearing said inclined groove, balls located approximately half in a recess in one part and in a groove in the other part and means for holding the 90 two parts and the balls together.

In testimony whereof I have affixed my signature.

JULIUS ALWIN LOTH.
